United States Patent Office

Des. 178,856
Patented Oct. 2, 1956

178,856

HOUSEHOLD MIXER

Walter C. Anderson, Fairfield, and Paul O. Rawson, Jr.,
Trumbull, Conn., assignors to General Electric Company, a corporation of New York

Application March 7, 1956, Serial No. 40,497

Term of patent 14 years

(Cl. D44—1)

Fig. 3.

Fig. 4.

We claim:

The ornamental design for a household mixer, substantially as shown.
